OSCAR M. PROVORSE AND RUSSELL C. SUTHERLAND, OF WYNONA, OKLAHOMA.

PUMPING MECHANISM FOR OIL-WELLS.

1,401,440.

Specification of Letters Patent. Patented Dec. 27, 1921.

Application filed May 7, 1921. Serial No. 467,750.

To all whom it may concern:

Be it known that we, OSCAR M. PROVORSE and RUSSELL C. SUTHERLAND, citizens of the United States, residing at Wynona, in the county of Osage and State of Oklahoma, have invented certain new and useful Improvements in Pumping Mechanisms for Oil-WellS, of which the following is a specification, reference being had to the accompanying drawings.

This invention relates to oil wells, and particularly to the casing of the oil well and the working barrel thereof.

As practically all mineral oil is found in sand, some of the sand will be drawn into the working barrel of the well on every stroke of the pump, more particularly when wells are new. As many wells are very deep, there is a great pressure on the cups of the traveling valve in order to lift the oil to the surface. As sand is heavier than oil, it will remain in the bottom of the well casing or tubing, coming in contact with the packing cups on every stroke of the pump. This sand cuts the cups or wears them out. The sucker rods must then be pulled out and the cups or packing replaced with new ones.

The general object of the present invention is to so form the casing and working barrel of the oil well that the mixed oil and sand as it is drawn upward by the traveling valve will pass into the chamber where the sand may settle so that the packing cups of the several valves or pistons will not be subjected to constant wear from the action of the sand.

A further object is to provide a construction of this kind embodying a working barrel disposed within a relatively large casing, the working barrel communicating with the casing through perforations, and the construction being such that the oil is drawn upward through the standing valve and traveling valve, is forced outward through these perforations into this relatively large chamber surrounding the working barrel, the sand settling in the bottom of this chamber, while upon the reverse stroke of the sucker rods the oil in this chamber is forced upward and into the well tubing and so outward.

Other objects have to do with the details of construction and arrangement of parts as will appear more fully hereafter.

Our invention is illustrated in the accompanying drawings, wherein:

Figure 1 is a vertical sectional view of the working barrel of an oil well pump constructed in accordance with our invention; 60

Fig. 2 is a section on the line 2-2 of Fig. 3;

Fig. 3 is a section on the line 3-3 of Fig. 1.

Referring to the drawings, 10 designates the tubing extending downward from the casing head of the well and 11 a head or bushing which at its upper end has screw-threaded engagement with the tubing 10 and which is annular in cross section, this head being formed with a socket 12 on its under face for the reception of the working barrel and being exteriorly screw-threaded for engagement by a coupling 13. This head is formed with a plurality of ducts 14 arranged in two annular series and extending upward and inclined from the under face of the head to the inner face thereof and discharging into the central aperture or passage of the head. The greatest diameter at the lower end of the head 11 may be 5 $\frac{1}{16}$ ", though, of course, other dimensions may be used, while the smallest diameter at the upper end of the head is approximately 2". The recessed portion 12 is formed to provide a shoulder to rest upon the working barrel 15, which will be approximately 12" in length and 2" in diameter and which is perforated at 16.

Engaging the head 11 by means of the coupling 13 is a length of 5 $\frac{1}{16}$ " pipe, designated 17, concentric to the working barrel and approximately 20' long. The lower end of this casing pipe 17 is exteriorly screw-threaded for engagement by a coupling 18 and this coupling engages with an annular head 19 having a central aperture and engaged with a perforated pipe section 20 by means of a coupling 21 or in any other suitable manner. Oil enters through the perforated pipe section 20 and discharges into an oil pipe 21 whose lower end has threaded engagement with the head 19 and whose upper end is engaged with a collar 22, which in turn forms a seat for the lower end of the working barrel and for the standing valve 28, which may be of any usual or suitable construction and is formed with the usual steel ball and seat therefor.

Operating within the working barrel 15 is 110

a sucker rod section 29 having screw threaded engagement with a $1\frac{1}{4}$ " "blind" valve, designated 30, whose cups are reversed. Connected with this blind valve 30 which 5 constitutes a piston is a sucker rod section 31, which in turn is connected to the $1\frac{1}{4}$ " working or traveling valve 32 of the usual construction.

While we have given the preferable dimensions of the several pipes constituting 10 the working valve and casing and the dimensions of the several valves, obviously these dimensions may be varied without in any way departing from the principle of the invention.

In the operation of this mechanism, it will be obvious that as the sucker rods are reciprocated in the usual manner that oil will be drawn upward through the perforations 20 of the pipe section 20, through the standing valve and into the space above the standing valve, and that upon the downward movement of the traveling valve this oil will be forced through the traveling valve and that 25 as the pump rods reciprocate the oil will be forced into the chamber formed between the head 11 and the head 19 and between the working barrel and the outer pipe 17 and that in this chamber the sand will tend to 30 settle and will gather at the bottom of the chamber, as indicated diagrammatically in the drawings, while the oil will travel upward and be forced out through the ducts 14 into the space above the piston or blind 35 valve 30 and in the reciprocation of the pump rods will be carried upward in the usual manner. Thus the sand will not remain in the working barrel as it does today, but will be drawn out with the oil into the 40 relatively large chamber surrounded by the wall 17 and will settle to the bottom of this chamber, while the oil without the sand will be carried upward. Thus the valves of the 45 standing valve and the traveling valve will not be cut or worn by the sand and will last much longer than they would if this sand drawn up through the standing valve was not forced out into the settling chamber.

It will be noted that the oil passes upward 50 through the lowermost head 19, upward through the standing valve, through the traveling valve, and that the sand and oil passes out through the perforation in the steel barrel 15, into the relatively large chamber, and 55 that the oil in this chamber is retarded in its upward travel owing to the relatively large size of this chamber and that as a consequence of this retardation, the relatively heavy sand will settle to the bottom of 60 the chamber where it lies unobstructed while the oil passes on upward in the usual manner. Should any sand find its way to the top of the barrel, it will be liable to work downward past the blind valve 30 as the 65 cups are reversed, and this sand will again

be discharged out through the perforations 16 into the settling chamber where it would again have a chance to settle at the bottom.

Of course, the size of the working barrel may be changed without necessarily changing the size of the pipe 17. Thus, for instance, the working barrel might have a diameter of 4" instead of a diameter of 2". It will be understood, of course, that the exterior barrel 17, if it has a diameter of 75 $5\frac{3}{16}$ ", would be used with casing of 6 $\frac{3}{8}$ " pipe, this being the ordinary size of the casing.

We claim:

1. In an oil well, a working barrel having a standing valve in its length and perforated above the standing valve, a barrel exterior to the working barrel and spaced therefrom, the space between the working barrel and the exterior barrel being closed at its lower end, a head closing this space at the upper end and having ducts opening into the upper end of the working barrel, a sucker rod, a traveling valve mounted on the lower end of the sucker rod, and a blind valve mounted upon the sucker rod above the standing valve, the blind valve and traveling valve being located normally below and above the perforations respectively.

2. In an oil well, a working barrel, a barrel exterior to the working barrel and spaced therefrom to form a settling chamber, the settling chamber being closed at its lower end and opening into the working barrel at its upper end, the working barrel having openings communicating with the settling chamber above the bottom of the latter, and means for alternately drawing oil upward into the working barrel and forcing it out through said openings and drawing the oil up through the upper end of the said chamber into the upper portion of the working barrel.

3. In an oil well, a working barrel, a pipe section operatively connected thereto and extending below the working barrel and having an inlet at its lower end, a standing valve disposed in the working barrel, an exterior barrel having a head at its lower end connected to the lower end of the working barrel, the exterior barrel being spaced from the working barrel to form a chamber, a head closing the upper end of this chamber and having ducts leading into the upper end of the working barrel, and a sucker rod operating within the working barrel having at its lower end a traveling valve and above its lower end a piston, the working barrel intermediate its ends having perforations leading into the exterior chamber.

4. In an oil well, a working barrel, a pipe section operatively connected thereto and extending below the working barrel and having an inlet at its lower end, a standing valve disposed in the working barrel, an exterior barrel having a head at its lower end con-

- 5 nected to the lower end of the working barrel, the exterior barrel being spaced from the working barrel to form a chamber, a head closing the upper end of this chamber and having ducts leading into the upper end of the working barrel, and a sucker rod operating within the working barrel having at its lower end a traveling valve and above its lower end a piston, said piston having its 10 cups reversed relative to the cups of the standing valve, the working barrel intermediate its ends having perforations leading into the exterior chamber.
5. In an oil well, an oil pipe, a head engaged with the oil pipe and having a recess in its lower face, a working barrel having its upper end disposed in said recess, a pipe section operatively connected to the lower end of the working barrel and forming a 15 continuation thereof, a head operatively connected to the lower end of the pipe section and supporting it, an exterior barrel operatively connected to the lower end and to the upper head and constituting a settling chamber, the upper head having ducts leading from the upper end of the exterior chamber into the central aperture of the upper head, a standing valve disposed at the lower end of the working barrel, a sucker rod, a traveling rod carried at the lower end of the 20 sucker rod and above the standing valve, and a piston carried upon the sucker rod above the traveling valve and having its cups reversed relative to the standing valve, the working barrel intermediate its ends having perforations leading into the exterior 25 chamber.
- 10 20
5. In an oil well, an oil pipe, a head engaged with the oil pipe and having a recess in its lower face, a working barrel having its upper end disposed in said recess, a pipe section operatively connected to the lower end of the working barrel and forming a continuation thereof, a head operatively connected to the lower end of the pipe section and supporting it, an exterior barrel operatively connected to the lower end and to the upper head and constituting a settling chamber, the upper head having ducts leading from the upper end of the exterior chamber into the central aperture of the upper head, a standing valve disposed at the lower end of the working barrel, a sucker rod, a traveling rod carried at the lower end of the sucker rod and above the standing valve, and a piston carried upon the sucker rod above the traveling valve and having its cups reversed relative to the standing valve, the working barrel intermediate its ends having perforations leading into the exterior chamber.
